Engr 2 27

UNITED STATES PATENT OFFICE.

ROBERT A. CONNOR, OF PHILADELPHIA, PENNSYLVANIA.

IDENTIFICATION DEVICE FOR CARS, VEHICLES, ETC.

Application filed July 21, 1922. Serial No. 576,551.

To all whom it may concern:

Be it known that I, ROBERT A. CONNOR, a citizen of the United States, residing at Philadelphia, in the county of Philadelphia and State of Pennsylvania, have invented certain new and useful Improvements in Identification Devices for Cars, Vehicles, Etc., of which the following is a specification.

10 This invention relates to identification plates, license tags and the like, for automobiles, freight cars, street cars, etc., and the primary object of the invention is to provide novel means whereby the number 15 of the identification plate, tag or the like, can be easily and quickly read at a relatively long distance both day and night, thereby effectively enhancing the usefulness of said plates and tags.

20 Another object of the invention is to provide an improved license plate or tag, in which colored panels are used in lieu of numbers or in connection with numbers, each colored panel representing a certain 25 numeral, the colored panels permitting the easy reading of the number at a relatively great distance.

20 A further object of the invention is to provide a license plate or identification tag embodying a colored code for night, and a colored code for day, the codes being the same with the exception that the codes are so constructed that the reading thereof is facilitated at day and night.

35 A further object of the invention is to provide an improved identification plate or tag embodying a face plate carrying a plurality of transparent or translucent colored plates in rear of which an illuminating lamp is adapted to be placed and a plurality of opaque plates of different colors, the transparent or translucent colored plates facilitating the reading of the number at night, while the colored opaque plate facilitates the reading of the number during the day time.

40 A further object of the invention is to provide an identification plate or license tag having colored transparent or translucent plates representing the number of the tag or plate, a plurality of opaque colored plates representing the number of the tag or plate, and the number of the tag printed or otherwise delineated between the transparent or translucent plate and the colored opaque plate, like colors and the numerals

50 of the number being arranged in alignment, whereby persons will be enabled to become familiar with the code by association of the numerals of the license number with the colored panels.

55 A still further object of the invention is to provide novel means for holding the different colored opaque and transparent or translucent panels in place on the face plate.

60 A still further object of the invention is to provide an improved license plate or identification tag of the above character, which will be durable and efficient in use, one that will be simple and easy to manufacture, and 70 one which can be placed upon the market at a reasonable cost.

75 With these and other objects in view, the invention consists in the novel construction, arrangement and formation of parts, as will be hereinafter more specifically described, claimed and illustrated in the accompanying drawings, forming a part of this specification, in which drawings:

80 Figure 1 is a perspective view of a motor vehicle, showing the improved license plate or tag associated therewith.

85 Figure 2 is a transverse section through the improved license plate or tag showing the means of connecting the same with the rear fender of a motor vehicle.

90 Figure 3 is a vertical longitudinal section through the improved device, taken on the line 3—3 of Figure 2.

95 Figure 4 is an enlarged horizontal section, taken on the line 4—4 of Figure 2, showing the means of holding the face plate carrying the codes in position against movement.

100 Figure 5 is a front elevation of a modified form of license plate or identification tag, which can be used on freight cars, street cars or the like.

105 Referring to the drawings in detail, wherein similar reference characters designate corresponding parts throughout the several views, the letter A, indicates the improved device for use as a license plate for motor vehicles; and B, a motor vehicle with which it is associated.

110 The motor vehicle B is of course, of the ordinary or any preferred construction or type, and forms no part of the present invention and has been merely shown for illustrating one use of the invention. As shown, the motor vehicle B includes a left hand rear fender 10, to which the improved license plate or device may be attached.

While I have shown the improved license plate or device A connected with the rear left hand fender 10 of the motor vehicle B, it is to be understood that the same can be associated with any other part of the vehicle that may be preferred or desired.

The improved license plate or device A comprises essentially a box or casing 15, in which is adapted to be positioned an illuminating lamp 16 such as of the electric incandescent type, and this lamp 16 can be connected with the usual storage battery of the motor vehicle. As shown, this housing or light casing 15 includes upper and lower opaque walls 17 and 18, side walls 19 and a rear hinged wall 20, which may be held in its closed position by a suitable catch or the like 21. This hinged rear wall 20 may carry a suitable reflector 22 for the electric lamp 16 if so desired. The rear end of the light casing 15 may be closed by a portion of a face plate 25 which carries the night code C for the license number and the day code D for the license number. As shown intermediate the day and night codes C and D the license number is written or delineated in the ordinary manner as indicated by the reference character E. This face plate 25 extends the full length of the casing 15, is relatively wider than the casing, is pivoted at a point intermediate its ends as at 26 to the lower wall 18 of the light casing 15, and is adapted to swing in front of the open rear face of the casing and position the night code C in front of the illuminating lamp 16. The upper inner face of the base plate 25 carries suitable angle brackets 27 which are provided with aligned openings which register with openings in the side walls 19 of the light casing 15. A suitable rod 28 is adapted to extend through these registering openings, and one end of the rod is provided with a head 29, and the opposite end with a diametric opening 30, through which a seal 31 is adapted to be placed so as to prevent the removal of said rod by unauthorized persons without detection. The night code C includes a plurality of translucent colored plates 32, 33, 34, 35 and 36 and these plates are of different colors, and each color represents a certain number. As shown, the plate 32 is of a blue color, which in this instance represents the numeral 3. The plates 33 and 34 are of a red color, which in this instance represents the numeral 2, and the plates 35 and 36 are green, and indicate the numeral 1. The portion of the base plate 25 which lies in front of the lamp 16 is provided with an inwardly extending slot 37 extending the full length of the plate and this slot extends inwardly from the upper edge of the plate to a point short of the intermediate or longitudinal axis thereof, and the colored plates 32, 33, 34, 35 and 36 are adapted to be positioned in said slot, the plate being pro-

vided with spaced openings 38 through which the translucent plates are adapted to be seen. It can be seen that at night, when the lamp 16 is turned on, the light rays therefrom will emanate through the translucent plates 32, 33, 34, 35 and 36.

The day code D includes a plurality of colored opaque panels or plates 39, 40, 41, 42 and 43, and these plates are colored identically the same as the translucent plates 32, 33, 34, 35, and 36 and represent the same numbers. The portion of the plate 25 below the light casing 15 is provided with a longitudinally extending guide way or slot 44 which extends inwardly from one transverse edge thereof toward the other edge, and ends short thereof. The opaque colored panels or plates are adapted to be placed in the guideway and the plate is provided with suitable transverse openings 45 through which the panels can be seen. The end of the base plate 25 through which the longitudinally extending slot 44 opens out, is provided with a transverse opening in which a removable pin 46 is adapted to be placed, and one end of this pin can be apertured for the reception of a suitable seal 47, whereby the pin cannot be removed by unauthorized persons without detection. When this pin 46 is in position the removal of the opaque panels is of course prevented. It is also to be noted at this time, that when the face plate 25 is in its normal position with the rod 28 in place, the removal of the translucent panel is also prevented in view of the fact that the top wall 17 overhangs the upper edge of the plate 25 and thus closes the slot 37 through which the translucent panels are placed.

Intermediate the night code and day code C and D is left a blank space on which the license number can be written or delineated in the ordinary manner, as indicated by the reference character E, and it is to be noted that the translucent plates and opaque plates of like colors are arranged in alignment and the numerals which stand for the different colors are placed in alignment with the colors for which they stand, thus facilitating the reading of the license plate and permitting the public to become familiar with the color code. It is to be understood, of course, that a different color is provided for each number from 1 to 9 and for zero.

In Figure 5 of the drawings is shown a slightly modified form of the invention which can be utilized for freight cars and the like, if so desired, and this form is constructed substantially the same as the form previously described with the exception that the number of the license or car is not written intermediate the night and day codes and the space between said codes is reduced in height.

From the foregoing description, it can be seen that a novel identification plate or license tag has been provided, embodying a colored code representing the number of the license plate or identification tag, and which embodies means whereby the code can be readily read both day and night.

Changes in details may be made without departing from the spirit or scope of this invention; but,

I claim:

1. An identification device including a casing having an open side, a lamp in said casing, a plate connected intermediate its edges to said casing so that a portion of the plate normally overlies the opening, said plate provided with openings permitting rays of light from said lamp to pass therethru and recesses at that portion of the plate, which does not overlie the casing, translucent sign panels in said openings of the plate constituting a night code and opaque panels in said recesses constituting a day code.
2. An identification device including a casing having an open side, a lamp in said casing, a plate connected intermediate its edges to said casing so that a portion of the plate normally overlies the opening, said plate provided with openings permitting rays of light from said lamp to pass therethru and recesses at that portion of the plate which does not overlie the casing, translucent sign panels in said openings of the plate constituting a night code, opaque panels in said recesses constituting a day code, and numerals delineated on said plate between the openings and recesses thereof, substantially as and for the purpose set forth.
3. An identification device including a casing having an open side, a lamp in said casing, a plate covering said opening and extending beyond one marginal edge of said casing, said plate provided with openings permitting rays of light from said lamp to pass therethru, translucent panels in said openings of said plate constituting a night code by use of different colors, and opaque panels carried by the extending portion of said plate constituting a day code by colors corresponding to those of the night code.
4. An identification device comprising a casing having one wall thereof open, an identification plate pivotally secured intermediate its ends to the lower wall of said casing and having a plurality of longitudi-
- nally aligned openings formed therein, and a longitudinally extending slot bisecting a portion of said plate and communicating with said openings, said slot extending from the upper edge of the plate to a point short of the longitudinal center thereof, a plurality of translucent different colored panels representing different numbers disposed in said slot and exposed at said openings, the upper end of said plate lying inwardly of the casing, angle brackets carried by the plate, the casing and angle brackets having aligned openings formed therein, a rod detachably fitted in said openings, and means for preventing the removal of said rod by unauthorized persons.
5. An identification device comprising a casing having one side thereof open, an identification plate pivotally secured intermediate its ends at the lower wall of said casing and having a plurality of longitudinally aligned openings formed therein and a longitudinally extending slot bisecting a portion of the plate and communicating with said openings, said slot extending from the upper edge of the plate to a point short of the longitudinal center thereof, a plurality of translucent different colored panels representing different numbers disposed in said slot and exposed at said openings, the upper end of said plate lying inwardly of the casing, angle brackets carried by the plate, the casing and angle brackets having aligned openings formed therein, a rod detachably fitted in said openings, means for preventing the removal of said rod by unauthorized persons, and a plurality of opaque different colored panels carried by said plate disposed in vertical alignment with the translucent panels.
6. An identification device comprising a casing having one wall thereof open, a lamp in said casing, an identification plate pivotally secured to said casing closing said opening and having a plurality of aligned openings formed therein and a slot bisecting a portion of the plate and communicating with said openings, said slot open to the top of said plate, said opening of the slot concealed by said casing when said plate closes the opening of the casing, a plurality of translucent different colored panels representing different numerals disposed in said slot and exposed at said openings, and means for holding said plate in a closed position.

ROBERT A. CONNOR.
